APPARATUS FOR THE DISTILLATION OF
DRY CLEANING LIQUIDAlfred Jones, London, England, assignor to W. M.
Still & Sons Limited, London, EnglandApplication March 30, 1934, Serial No. 718,159
In Great Britain August 11, 1933

2 Claims. (Cl. 196—15)

This invention relates to dry cleaning apparatus in which clothes or other articles to be cleaned are washed with benzine or other cleansing liquid which is recovered by distillation and condensation for reuse.

Dry cleaning apparatus is known in which a still receives dirty liquid from a washing chamber and the sludge or residual liquid from this still is discharged from time to time into an auxiliary still, the distilled vapours from both the main and the auxiliary still being led to a common condenser whence the condensate is returned to the apparatus for reuse.

When sludge or dirty residual liquid is heated sufficiently to evaporate the volatile constituents in reasonable time, it is found that almost invariably it froths to such an extent that froth is carried out of the still with the vapour and, if this frothy vapour is condensed and returned for reuse as cleansing liquid, contamination of the cleansing liquid results.

Objects of the present invention are to provide improved means for withdrawing from the system dirty distillation residues and for heating up the used liquid before it is distilled.

According to the present invention dirty distillation residues are withdrawn from a main still and discharged into a supplementary still through a pipe connecting the bottom of the main still to the top of the supplementary still the said pipe also serving to condense the vapour distilled from the liquid in the supplementary still and return the distillate to the main still. The main still is connected with a chamber which receives the used cleansing liquid from the cleaning chamber and in which, before passing to the main still, it is preheated by hot circulation water from the condenser of the main still, with or without the aid of water of condensation from the stills when the latter are steam heated. The preheating vessel is preferably fitted with a removable strainer for intercepting buttons and other small objects and has its top connected to the bottom of the main still by a pipe through which the preheated cleansing liquid overflows as additional used cleaning liquid is discharged into the preheating vessel from the cleaning chamber.

In the accompanying drawings, Fig. 1 shows the apparatus mainly in elevation; Fig. 2 is a sectional elevation at right angles to Fig. 1 showing the cleaning chamber and basket and the preheating vessel.

The apparatus comprises a standard or frame *a* having fixed to its upper part the end cover *b* of the cleaning chamber which is constituted by a

cylindrical vessel *c* bolted to the said end cover and having, at its opposite end, an upwardly inclined inlet passage *d* closed by a door *e* preferably hinged at its edge *e*¹ and carrying, on an inwardly extending bracket *e*², a closure *e*³ for an aperture in the end of a clothes-containing basket *f* which is secured to a driving spindle *g* extending through a stuffing box *h* in the fixed end cover *b* and mounted in roller bearings in the standard or frame *a*. The door-carried closure *e*³ prevents the clothes escaping from the basket during its oscillation into the chamber *c*. A pinion *i* on the spindle gears with a toothed rack *k* actuated by a crank *l* driven through worm gear from an electric motor *m*. To avoid shock it is preferred to interpose in the connection between the crank and the toothed portion of the rack a spring buffer arrangement comprising a telescopic joint with springs *n*.

Beneath the chamber *c* is a liquid straining and heating vessel *o* which is formed with a neck *o*¹ that has a lateral connection *o*² with the bottom of the chamber *c*; this connection is provided with a cock or valve *o*³ and may be formed with a coupling piece to enable the vessel to be detached. The mouth of the neck is closed by a screw cap *o*⁴ having linked to it a short length of tube *o*⁵ which rests on a shoulder in the neck and projects downwardly. Attached to the tube is a gauze pocket or strainer *o*⁶ which retains buttons and so on entering with the cleansing liquid and can be easily withdrawn for emptying. The entering liquid is directed to the bottom of the vessel *o* by a tube *o*⁷ (Fig. 2). Within the vessel *o* is a coil *p* for circulation of water of condensation led from the steam heated main still *q* through the pipe *q*¹; and the lower part of the vessel is jacketed and heated by water led from the condenser *r* through the pipe *r*³. Towards the top, the vessel *o* has an outlet pipe *s* connected to the still *q*, the upper part of which is connected by a pipe *t* to the elevated condenser *r* which consists of coils arranged within a water tank and discharging into a cleansing liquid storage tank *u* which is in valve-controlled connection through the pipe *v* with the chamber *c*.

To avoid the necessity of frequently opening up the still *q* to remove dirty residue, it is so connected with a supplementary still *z* that the dirty residue can be withdrawn from the bottom of the still *q* and delivered into the still *z*, the ultimate residue being drawn off through a cock *z*¹; in the example, a pipe *q*² extends from the bottom of the still *q* and is connected to the top of the still *z* through a condensing coiled pipe *z*² and through

a hand operated pump *w*. The still is heated by steam piping *z*³ arranged in the bottom of the still and connected to the coil *q*³ arranged in the main still. With this arrangement, the distilled vapour condenses in the pipe *z*² and the distillate flows back through the pipe *q*² to the still *q* thus avoiding froth, due to heating of dirty liquid, being carried away with the vapour into the condenser *r* and thence to the storage tank *u* which would result in contamination of the liquid to be used for cleaning. Residue accumulating in the still *q* can be pumped at any time into the still *z*, whilst, when steam is shut off from the still *z*, condensation of vapour therein will cause a reduction of pressure and any residue in still *q* will be sucked up the pipe *z*² into the still *z* ready for future distillation.

What I claim is:—

1. In an apparatus of the character described, 20 cleansing liquid recovery means comprising, a main still for distilling dirty cleansing liquid, a condenser, a connection between said still and condenser through which the distillate can pass, a supplementary still, between the main still and the supplementary still, a pump adapted to with-

draw the residue from the main still and deliver it into the supplementary still and an open connection between the bottom of the main still and the top of the supplementary still, said open connection serving as a condensing device for distilled vapour from the supplementary still and as a return for the condensate to the main still and to permit residual liquid in the main still passing into the supplementary still when the heating of the latter is stopped. 10

2. In an apparatus of the character described, a main still for distilling dirty cleansing liquid, a condenser, a connection between said still and condenser through which the distillate can pass, a supplementary still having its top positioned 15 above the level of liquid in the main still and, between the bottom of the main still and the top of the supplementary still, an open condensing pipe connected to said main still and adapted to permit passage of residue from said main still 20 into said supplementary still upon diminution of pressure in the latter and also to permit condensate from the supplementary still to gravitate into the main still.

ALFRED JONES. 25
